UNITED STATES PATENT OFFICE.

OTTO F. BRUMAN, OF ZURICH-ENGE, SWITZERLAND, ASSIGNOR TO FESTA A. G., OF ZURICH, SWITZERLAND.

WATER-HEATING FAUCET.

Application filed April 13, 1921. Serial No. 461,079.

To all whom it may concern:

Be it known that I, OTTO F. BRUMAN, a citizen of the Swiss Republic, and a resident of Zurich-Enge, Switzerland, have invented 5 a new and useful Improvement in Water-Heating Faucets, of which the following is a full, clear, and exact description.

My invention relates to improvements in that class of faucets which have electrical 10 attachments for heating the flowing water, and in which the liquid itself acts as a resistance medium. The object of my invention is generally to produce a simple, practical, and convenient faucet which can be 15 connected in the ordinary metallic way with the supply pipe without fear of loss of current, and which has the electrodes supported on the barrel of the faucet in such a way as to be perfectly insulated, with the 20 electrodes one within the other, and in which the faucet can be operated in the usual way and made to permit cold water to run freely through it, in which case the electric current is cut out, or which can be 25 turned so that the flowing water will pass between the electrodes in such a manner as to be heated by electric resistance. This 30 arrangement is effected by a switch on the spindle of the faucet which when turned a certain distance, opens the faucet to the flow 35 of water, but cuts in the current to the electrodes, thereby heating the water, and which when turned a further distance cuts out the current but permits the water to 40 flow freely. The invention is further intended to produce an economical arrangement of the electrodes by which the current will be used to advantage in heating the water quickly, and in which there is little 45 danger of current leakage. The invention is further intended to provide a casing for the electrodes through which the water flows, and to construct the casing with safety outlets so that there is no danger of the water 50 rising under any circumstances and short circuiting the heating apparatus. These and other advantages will appear from the description which follows.

Reference is to be had to the accompanying drawings forming a part of this specification, in which similar reference characters indicate corresponding parts in all the views.

Figure 1 is a vertical longitudinal section through the apparatus, and 55

Figure 2 is a diagrammatic view of the electrodes and connections.

The drawings are shown by way of example, and some of the details may be departed from without affecting the invention. 60 I have shown a conventional faucet body or barrel 10, having the customary screw connection 11 with the water supply pipe 12. The barrel 10 has the customary bore 13 at its inner end, and at the outer end of the bore 65 is a seat 14 for the needle valve on the end of the spindle 15, which is a conventional arrangement, and the spindle screws in and out as usual. The spindle is provided with a suitable handle 16 at its outer end for 70 turning it.

Suspended on the barrel 10 and properly spaced thereon is an insulating body 17 having a bore 18 vertically therethrough, and this registers with a port 19 in the 75 faucet body so that when the faucet is open the water will flow freely through the bore 13, port 19, and bore 18.

At the lower end of the body 17 is a tubular electrode 20, the bore of which registers 80 with the bore 18, and this is surrounded by a cup-shaped electrode 21 of the same cross-sectional shape as the electrode 20, and this also is fastened at its upper end to the insulating body 17, and as shown the latter 85 is reduced as at 17^a to permit the electrode 21 to fit nicely thereon. The electrode 21 is closed at the bottom except for a vent 21^a and this can be closed by insulating material if desired, as shown in Figure 2. The member 90 21 is preferably covered by a protective insulation 21^b.

Through the upper part of the electrode 21 are ports 22 through which the water can flow, and both electrodes 20 and 21, as well 95 as the lower part of the insulating body 17, are enclosed in a casing 23, which can if desired be of metal, and which is thoroughly insulated from the electrodes by the member 17 and by the spacing distance. The members 20 and 21 are spaced so that the water flowing between them will offer sufficient resistance to be quickly and thoroughly heated, and the casing 23 is spaced sufficiently from the electrode 21 so that there will be no loss 100 of current in this way, and this is addition-

ally safeguarded by the protective insulating coating 21^b.

- At the lower end of the casing 23 is an outlet 24 above which is preferably arranged 5 a screen 25, and spaced apart from the main outlet, and arranged around the casing, is a gallery of openings 25 through which the water may flow if it rises to this height. By reference to Figure 1 it will be seen that 10 these openings are made so that the down flowing water will not pass through them, but that the rising water will. The object of this arrangement is to prevent any possible short circuiting, and if the main outlet 15 becomes clogged, or the sieve 25 becomes clogged, the water rising will flow out through the openings 25 and can by no possibility rise to a sufficient height to short circuit the apparatus.
- 20 A convenient way to make the holes 25 so that the down flowing water shall not pass out through them, is to punch in the metal of the casing so as to leave shieldlike members 26 on the inner side, or if the casing is 25 not of metal, these can be otherwise formed to produce the same result.

The spindle 15 of the faucet carries a switch 27 on which are contacts 28 which can be conveniently flat springs, and these 30 are adapted to make contact with the segmental contacts 29 and 30 which are curved to the circles represented by the inner and outer parts of the contact pieces 28, and which can be supported in any suitable way. 35 One of the contact members 29 connects by a wire *a* with the positive supply wire A, and the other connects by the wire *b* with the return wire B. One of the contacts 30 connects by a wire *c* with the inner electrode 20, 40 and the other contact piece 30 connects with the outer electrode 21 by the wire *d*. It will be seen then that when the valve is opened and turned to a certain distance, the water will flow through, and the spring contacts 45 28 will close the circuit through the contact pieces 29 and 30 and through the electrodes, the current flowing from the wire A, through the wire *a*, a contact piece 29, one of the spring contacts 28, the contact piece 30, the 50 wire *c*, the electrode 20; the water passing between the two electrodes to the outer electrode 21, the wire *d*, a contact piece 30, the second contact spring 28, the contact piece 29, and the wire *b* to the line wire B. 55 If the faucet is opened further, however, and the spindle 15 turned to a greater distance, the circuit is broken, because the contact springs 28 will pass off the contact strips, and cold water can then flow freely 60 through the faucet.

It will be seen from the foregoing description that the invention is very simple, that the electrodes are thoroughly insulated, that the faucet can have the usual metallic 65 connections, that there is no danger of leak-

age of current, and that the connection of the casing 23 with the faucet barrel 10 is such that there is no chance for leakage through hygroscopic action.

I claim:—

- 70 1. A water heating attachment for faucets comprising an insulating body directly connected to the faucet barrel, said body having a bore extending through it and connecting with the bore of the faucet barrel, a cup-shaped electrode suspended from the insulating body and provided with ports near its upper end, and a shorter and second electrode having a bore extending therethrough 75 enclosed in and spaced apart from the cup-shaped electrode, said electrode being directly connected with the insulating body so as to register with the bore thereof. 80
2. An attachment for faucets according to claim 1, characterized by the further fact 85 that the cup-shaped electrode is provided with an exterior insulating coating. 90
3. A water heating attachment for faucets comprising an insulating body suspended from and directly connected to the barrel 95 of the faucet and provided with a bore connecting with the bore of the faucet, an inner electrode connected with the insulating body and having a bore therethrough aligning with the bore of said insulating body, a cup-shaped electrode suspended directly from the insulating body and entirely enclosing the inner electrode, said cup-shaped electrode having ports through the upper part thereof, and a casing enclosing the insulating body and the electrodes, said casing having an outlet at a point below the bottom of the cup-shaped electrode. 100
4. A water heating attachment for faucets comprising an insulating body having a bore to receive the barrel of a faucet and having a vertical bore connecting with the bore of the faucet, inner and outer electrodes suspended from the insulating body and spaced apart therefrom, the outer electrode 105 being closed at the bottom and provided with side ports, and a casing enclosing the electrodes and insulating body, said casing having a bottom vent and emergency vents in the sides at points above the lower vent. 110
5. A water heating attachment according to claim 4 in which the emergency vents are characterized by having shields above them whereby the down-flowing water will not pass through them but the rising water will. 115
6. A water heating attachment for faucets comprising an insulating body adapted to be supported on a faucet barrel and having a bore therethrough to connect with the bore of a faucet, a tubular electrode supported on 120 the insulating body and registering with the bore of said body, a generally cup-shaped electrode also supported on the insulating body and surrounding and spaced apart from the first electrode, said outer electrode 125 130

having water openings through the upper part thereof, a casing enclosing the electrodes and having a main discharge outlet at the lower part, and emergency outlets 5 above said main outlet and below the bottom of said outer electrode.

7. A water heating faucet comprising a barrel having a valve spindle thereon to open and close the faucet, and a transverse port 10 behind the valve end of the spindle, an insulating body supported on the barrel and having a bore to register with the port of the faucet, a tubular electrode suspended on the insulating body and registering with the 15 bore thereof, an outer generally cup-shaped electrode supported on the same insulating

body as the inner electrode and surrounding the said inner electrode, said outer electrode having openings for water through the upper part thereof, a casing enclosing both 20 electrodes and spaced apart from the outer electrode, said casing having suitable vents for water, a switch on the faucet spindle arranged to cut in electric current to the electrodes when the faucet is opened a certain 25 distance, and to cut out the current when the faucet is opened wider, and electrical connections.

OTTO F. BRUMAN.
